UNITED STATES PATENT OFFICE.

CLARENCE M. STARNER, OF GARDNERS, PENNSYLVANIA, ASSIGNOR OF ONE-HALF TO
J. W. WIGLE, OF GOODYEAR, PENNSYLVANIA.

SNOW REMOVER.

Application filed June 2, 1924. Serial No. 717,863.

To all whom it may concern:

Be it known that I, CLARENCE M. STARNER, a citizen of the United States, residing at Gardners, in the county of Adams and State 5 of Pennsylvania, have invented new and useful Improvements in Snow Removers, of which the following is a specification.

This invention relates to means for removing snow from the rails of a track, and 10 contemplates the use of a pair of burners adapted to be suspended from a car into close proximity with the rails of the track ways, the burners having valve controlled communication with a fuel supply tank, 15 from which the fuel is conveyed to the burner under air pressure.

In carrying out the invention I provide a novel construction of means for supporting the burners for adjustment with relation to 20 the rails of the track, so that the snow can be quickly removed from either side of said rails, and also from the cross ties adjacent the rails.

The nature and advantages of the invention 25 will be better understood when the following detailed description is read in connection with the accompanying drawings, the invention residing in the construction, combination and arrangement of parts as 30 claimed.

In the drawings forming part of this application, like numerals of reference indicate similar parts in the several views.

On the drawings—

Figure 1 is a view showing how the invention is mounted upon a car, and the relation of the burners with respect to the rails 35 of the track.

Figure 2 is a sectional view taken on the line 2—2 of Figure 1.

Figure 3 is an enlarged view partly in section of one of the burners and its adjusting means,

Figure 4 is an enlarged view partly in section showing the means employed for adjusting the burner,

Figure 5 is a sectional view showing the manner in which the burner is supported.

Referring to the drawing in detail, A 50 indicates generally a car upon which is mounted the mechanism or device forming the subject matter of the present invention.

This device essentially consists of a pair of burners adapted to be arranged directly 55 above but in close proximity to the rails 10

of the track, this position of parts being clearly illustrated in Figure 2. These burners are adapted to be supplied with a liquid fuel contained in a tank 11 which is mounted on some appropriate part of the 60 car A. The tank is of course provided with a filling tube 12 normally closed by a removable cap. The fuel from the tank 11 is conveyed to the burners under compressed air pressure, and therefore I have indicated 65 at 13 a compressed air supply pipe which may lead from any suitable source, this pipe being coupled to an air supply pipe indicated at 14 and arranged to extend across the top of the tank 11. Depending from 70 pipe 14 are spaced parallel extensions which enter the tank 11 to supply the latter with air under pressure, both of which extensions are provided with valves 15 to control the communication between the air supply pipe 75 14 and the tank 11. Leading from one end of the pipe 14 is a fuel supply pipe 16, which is coupled to flexible pipe sections 17 which extend from the fuel supply pipe 16 80 to the burners arranged adjacent the rails 10 of the track. A valve 18 is carried by the coupling 19 to control the flow or passage of the fuel from the supply pipe 16 to the respective burners. The fuel is forced from the tank 11 under air pressure through a 85 pipe 20 which enters the tank 11 adjacent one end thereof, and which pipe 20 communicates with the pipe 14 at a point immediately adjacent the connection between this pipe 14 and the fuel supply pipe 16, 90 so that the fuel passes upwardly through the pipe 20 into the pipe 14, and thence into the supply pipe 16, from where it is conveyed to the respective burners. A valve 21 is arranged in the pipe 14 to prevent the 95 compressed air from passing through this pipe into the supply pipe 16, or this valve may be slightly opened to permit a portion of the air to pass directly through the pipe 14 into the supply pipe 16 if desired.

Each of the burners above referred to include spaced parallel pipes 22 and 23 respectively which are clearly shown in Figure 3, and arranged in spaced superimposed relation. Both of these pipes at one end communicate with each other through an elbow 24, while the lower pipe 23 of the burner is perforated as at 25 throughout its entire length. One end of the pipe 22 of the burner is offset as at 26, which end is cou- 100 105 110

pled to one of the flexible pipes 17 above referred to, while the corresponding end of the pipe 23 is closed. Consequently the fuel from the supply tank 11 is forced into one end of the pipe 22, and flows through this pipe into the pipe 23 through the elbow 24, and is burned along the line of perforations 25. Therefore the flame is arranged in close proximity to the rails 10, and quickly melts 10 and removes the snow from about the rails as will be readily understood. In order to provide a highly combustible mixture when the fuel enters the pipe 23, I arrange the pipe 22 directly above the pipe 23, so that 15 the pipe 22 is subjected to the heat of the burner and in this manner the fuel is pre-heated and vaporized in the pipe 22 before it enters the pipe 23. Furthermore to confine the heat about the pipe 22 for the purpose just mentioned I also make use of a 20 casing 27 which is of substantially semi-cylindrical contour in cross section, and which section embraces or houses the pipe 22, to confine the heat about this pipe.

25 The pipes 22 and 23 of each burner are supported by spaced collars 28, and each of these collars is formed with an annular groove 29 to receive a two part bearing as clearly shown in Figures 4 and 5. The respective parts of this bearing are indicated 30 at 30, which parts are hingedly connected together as at 31, and having their free ends extended to provide spaced parallel supports 32 which are riveted or otherwise suitably 35 secured to brackets 33 secured to the underside of the car A as illustrated. Consequently the burner including the collars 28 is supported by the bearings just described, the burner and collars being mounted for rotation 40 in said bearings, so that the flame from the burner can be properly directed against either side of the adjacent rail 10 as the occasion may require. The flexible pipes 17 connected with the respective burners allow 45 said burners to be partially rotated in either direction to properly direct the flame according to the conditions or circumstances.

For controlling the adjustment of the burners in the manner just mentioned, I provide 50 one of the collars 28 of each burner with a curved rack bar 34, and meshing with each rack bar is a toothed segment 35. Rising from each segment is a lever 36 which is journaled in a suitable bearing 37 supported 55 on the bracket 33. These levers 36 project

within the car A through slots 38 provided in the bottom or floor of the car, thus disposing said levers 36 within convenient reach of the operator, whereby said levers can be easily manipulated from inside of the car. 60 It will be seen upon rocking of the levers the bars will be rotated about their axes and thereby positioned so that the flame will be directed to the inside or outside of the rails 10. The invention is very simple in construction, easy to manipulate, and designed to remove snow and ice from about the rails of a track way, which cannot be otherwise easily removed by a snow plow or sweeper and accomplish the desired result in quick order. 70

75 While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:

1. Car carried means for removing snow 80 from the rails of a track, said means including burners supported beneath the car and arranged in close proximity to the rails, each burner including spaced pipes communicating with each other at one end, 85 means establishing communicating between the tank and each burner, spaced collars associated with each burner, bearings suspended from the car and in which said collars are mounted to support each burner for partial rotation in either direction, a rack bar secured to one of the collars, a lever mounted for pivotal movement and extended within said car, and a toothed segment carried by the lever and meshing with said rack bar, whereby said burner may be adjusted 90 with relation to the rails for the purpose specified.

2. An apparatus of the character described comprising a pair of bearings, a longitudinally extended burner, collars carried thereby and rotatably supported in the bearings, a rack bar carried by one of the collars, a pivoted handle, and a toothed segment meshing with the rack bar whereby upon manipulation of the handle, the collars will be adjusted axially to dispose the burner at various positions about its axis. 100

105 In testimony whereof I affix my signature.
CLARENCE M. STARNER.
